UNITED STATES PATENT OFFICE.

WILLIAM A. LORENZ, OF HARTFORD, CONNECTICUT, ASSIGNOR TO THE OTAKA FABRIC COMPANY, OF HARTFORD, CONNECTICUT, A CORPORATION OF CONNECTICUT.

PAPER CRINKLING.

Application filed February 16, 1921. Serial No. 445,286.

To all whom it may concern:

Be it known that I, WILLIAM A. LORENZ, a citizen of the United States, residing in Hartford, in the county of Hartford and 5 State of Connecticut, have invented certain new and useful Improvements in Paper Crinkling, of which the following is a specification.

This invention relates to gathering a web 10 of paper or paper pulp both laterally and longitudinally.

The web is first gathered laterally by forming lengthwise corrugations or flutings therein. These corrugations are preferably 15 parallel with the edges of the web, and may be made by passing the web between peripherally grooved rolls. The web is then gathered longitudinally by forming transverse crinkles therein.

Smooth or uncorrugated paper has usually been crinkled transversely by the employment of a stripper blade. A stripper blade engages the surface of the cylinder upon which the web is carried, and works 25 its way between the paper and the cylinder. A stripper blade forms an abrupt angle to the cylinder, and consequently the paper (which is moist and hence adheres to the cylinder) is crushed against the blade (usually termed a "doctor-blade"), and thereby 30 crinkled.

In my former application No. 346,310, now pending, is disclosed a doctor-blade formed with an undulating edge to fit the 35 grooves and ridges of a corrugated cylinder, so as to strip the paper from the cylinder and crinkle it.

A doctor-blade sets a relatively low limit to the speed of operation, because if the 40 cylinder advances the paper with too high velocity against the blade, the latter is apt to strip the paper improperly from the cylinder and tear it, especially if the paper is of low grade and weak, such as commonly used for towels, etc.

Accordingly, this invention dispenses with the use of a doctor or doctor-blade, and an 45 object of the invention is to enable the paper to be crinkled transversely at much higher speed than heretofore found practicable, and to minimize or avoid liability of rupture, so that not only high grade papers but also low grade material may be rapidly and safely crinkled after corrugation.

It is in order to accomplish this result

that the doctor-blade is eliminated. The novel crinkling set includes no stationary part. Instead, a second cylinder is arranged to co-operate with the main corrugated cylinder, the second cylinder being 60 also corrugated and meshing with the corrugations on the main cylinder, but out of contact therewith. The moist web, which is in corrugated condition as it is advanced around the main cylinder, is carried into a 65 throat formed by the co-operation of the two cylinders. In this throat the web is retarded by the second cylinder, which is geared to run at slower surface speed than the main cylinder; said cylinder being placed 70 so near each other that the second cylinder engages the web. The paper or web tends to choke up the throat, whereby the oncoming web is driven against the portion of 75 web that is choked in the throat, and thereby the oncoming web, in pushing the leading portion of web through the throat, is crushed or crinkled transversely throughout 80 its corrugations, and the paper or web emerges on the other side of the throat with 85 its corrugations traversed by crinkles. As it emerges, it may pass around the second cylinder at about the same speed as the latter, and carried off upon a delivery belt. The web thus passes between the members 90 of the crinkling set, with great advantage, as compared with the use of a doctor or doctor-blade, which turns the paper aside. Said second or crinkling cylinder is preferably provided with clearance to control 95 and improve the character of the crinkling; and this clearance may be in the nature of grooves cut or sunk in the periphery of the crinkling cylinder and extending longitudinally thereof, preferably parallel with 100 the axis of the cylinder, although the grooves may if desired run helically along the cylinder. These clearance grooves may be of nearly or about the same depth as the grooves which run around the cylinder, and hence may divide the peripheral ridges into sets of teeth, which enter the grooves in the main cylinder to engage the paper or material carried around by the latter, and retard the same, and hence duly effect the 105 desired crinkling. The teeth match the grooves in the main cylinder, but do not scrape or touch the latter, so that tearing or injury of the web is avoided. The paper or material will crinkle more readily in the 110

clearances than where gripped by the teeth, and hence the corrugated product may have an aspect of discontinuous or spotty crinkling, highly crinkled portions alternating with less crinkled or uncrinkled portions. The highly crinkled portions correspond with the longitudinal grooves in the crinkling cylinder, or with the peripheral spaces between the teeth, and hence the product may comprise panels of corrugated crinkled paper alternating with panels of plain corrugated paper, thus giving the product a pleasing appearance. This increases its salability, especially when the paper or product is subsequently run between plain calendering and burnishing rolls (shown in my application No. 440,869, filed January 29, 1921) in the manufacture of paper towels, for example. The uncalendered product, however, which is stretchable in all directions, is useful for many other purposes, such as bag linings, barrel linings, wall paper, etc., and a great variety of grades, weights and qualities of material may be treated in this manner.

The invention also overcomes a further difficulty which has been experienced in crinkling corrugated paper, which is that such paper, on account of its stiffness due to the corrugations, tends to spring away from the main cylinder, and hence is not driven thereby properly against the abrupt stripper blade or doctor-blade, which, by forcing itself between the web and the cylinder, has the effect of increasing the objectionable tendency of the web to separate from the cylinder. In attempting to overcome this difficulty, it has been usual to subject the corrugated paper, especially if heavy or stiff, to a great deal of moistening, to increase its tendency to adhere to the surface of the main cylinder, to enable the latter to drive and crush the paper. The present invention, however, is not in the nature of a doctor-blade, and does not exhibit its faults, but the second or crinkling cylinder, on the contrary, is effective to hold the corrugated paper down or bend it around the main or carrying cylinder, and minimize or overcome its tendency to spring away from said main cylinder. This result is also favored by the adaptability of the invention to be operated at high speed, inasmuch as the oncoming heavy paper is reduced to a crinkled condition in the throat before it has opportunity to become separated from the main cylinder in advance of the crinkling line. In the matter of speed, it will be seen that the invention possesses the advantage that if the speed of the main cylinder is increased, the speed of the crinkling cylinder increases with it, while the effect upon the paper or web continues about the same at high speed as at low speed. This increase of speed not only reduces the cost of pro-

duction, which is an essential item in making towels, for example, but also improves the character of the crinkling and the reliability of the machine, as, for example, in the case of crinkling heavy or stiff or partly dried papers, owing to the described bending of the paper around the main cylinder, and to the fact that the paper is crinkled without having opportunity to spring away from the cylinder.

The web is caused to hug the main cylinder or carrying roll closely, especially when the rolls are of relatively large diameter, thus extending the narrow portion of the throat and confining the uncrinkled advancing corrugated paper against springing away from the cylinder, so that more remote portions are bent down upon or caused to hug the cylinder.

A variety of designs upon the product may be produced by making appropriate variations in the crinkling cylinder. For example, the clearance grooves may be arranged as in right and left-hand helices, so that the grooves cross one another, and so that the teeth have an echelon arrangement.

The material employed is preferably a web or pulp or semi-pulp which is producible upon a paper machine before the web reaches the final point where it would be converted into paper. The pulp or semi-pulp is readily stretched by corrugating rolls in forming the longitudinal grooves, and the web, while still in moist condition, is then excellently crinkled by the fast and slow cylinders in the manner described, and the product may be dried and used for various purposes, or, if desired, it may be run through calendering and burnishing rolls for use as towels, etc.

Other features and advantages will herein-after appear.

In the accompanying drawings,

Figure 1 is a plan of an apparatus for carrying out the present improvements in one form.

Figure 2 is a sectional side elevation taken at about the line 2-2 of Figure 1.

Figure 3 is an enlarged sectional fragment to illustrate diagrammatically the crinkling operation.

Figure 4 shows a corrugating couple comprising a rubber, felt or other soft roll for corrugating the web longitudinally.

Figure 5 shows a belt for pressing the pulp material into the peripheral grooves of the main cylinder.

By using a portion of a paper-making machine, paper pulp is formed into a web 10. This web may be carried between rolls 11, 12, which press out the water. From these rolls the web may be led at 13 in a semi-pulp condition around a guide-roll 14, and thence around a main cylinder 15, forming a member of a crinkling set. In

this cylinder 15 are formed grooves 16 running side by side around its periphery.

Said cylinder 15 may preferably be used for forming corrugations in the web. Connected to the cylinder by gears 17, 18, is a

5 companion cylinder 19, having peripheral grooves 20 alternating with ridges 21, to mesh with cylinder 15 and force the paper into the grooves 16, whereby the web is longitudinally corrugated; the material because of its pulpy condition being capable of stretching or flowing laterally as far as required as an incident to rolling the corrugations, the web retaining substantially 10 its original width. The web may be otherwise corrugated, as, for example, by either of the means shown at Figures 4 and 5, hereinafter explained; and the invention is not limited to the use of pulp or semi-pulp 15 web, inasmuch as a web of finished paper, properly moistened, may be carried around the cylinder 15 for the purpose of crinkling or of both corrugating and crinkling the same.

20 25 The corrugated web, advancing around cylinder 15, enters a throat 22 formed by the co-operation with cylinder 15 of a crinkling cylinder 23, which is peripherally grooved at 24 to correspond with ridges 25 in cylinder 15, so that the cylinders may run in mesh. These cylinders are connected by means of a small gear 26 rigid with cylinder 15, and a large gear 27 rigid with cylinder 23, so that the latter runs at 30 a lower surface speed. The speed of 23 may be of any desired ratio, for different purposes.

35 The throat 22 gradually grows very narrow, inasmuch as the cylinders are set 40 closely together, as seen at Figure 3, or in intermeshing relation but without contact. It will be understood that the throat as viewed from above has an undulating configuration. The slowly moving cylinder 23 45 grips or touches the paper and retards it, causing the oncoming web to choke the throat and to form into transverse crinkles; and the longitudinally corrugated and transversely crinkled product is led 50 around slow cylinder 23 at 28 and carried off upon a delivery belt 29 to any suitable drying apparatus. Then, if desired, it may be smoothed out, calendered or burnished.

55 Preferably the crinkling cylinder or roll 23 is provided with numerous clearances in the nature of grooves 30 extending preferably parallel with the axis of the cylinder, and forming spaces into which the web can crinkle at short intervals, the character and 60 depth of the crinkling being controlled by the frequency and depth of the clearances 30 and by the intervals between the clearances. At the intervals the web is left substantially in an uncrinkled condition, so 65 that the crinkled portions or panels 31

alternate with uncrinkled portions or panels 32 in the product, forming a check-work, as indicated diagrammatically at 31^a.

The clearance grooves 30 form the ridges 70 of the crinkling cylinder into teeth 33, which mesh in the grooves 16 in the main cylinder 15, Figure 3. The rear face of each tooth is preferably radial, while the advancing face is preferably oblique, as illustrated at Figures 2 and 3; but the invention is not limited to this type of tooth. The web may crinkle against the rear edges 75 of each tooth, into the clearances between the teeth.

80 At Figure 4, the corrugations are effected by a cylinder 34, having thick facing or surface of a rubber compound or other soft material 35, which yieldingly presses the semi-pulp material 13 into the grooves on the main cylinder 15. Preferably this cylinder 34 has alternating peripheral grooves 36 and ridges 37 to mesh with the grooves and ridges in the cylinder 15; but in some cases the grooves 36 may be omitted, and a plain 85 soft cylinder used. The cylinders 34 and 15 press together, and the soft material 35 tends to pack the web into the grooves in the cylinder 15 without danger of rupturing or unduly weakening the web, and effects a satisfactory corrugation of the 90 fabric.

95 At Figure 5 there is arranged to co-operate with the grooved main cylinder 15 an endless belt 38, which runs over power-driven guide-rolls 39, 40, 41, and may be made of woven fabric or other material suitable to press the pulp material 13 into the grooves 16 of the cylinder 15; the belt being sufficiently tight for this purpose. 100

105 If the two cylinders 15 and 23 are rotated at the same speed, fabric may be embossed thereby, and this method has many advantages over the ordinary method of embossing. For embossing, the main roll 15 may have a facing of a suitable soft rubber compound, and the cylinders may be pressed together, so that the embossing design upon the embossing cylinder may be 110 pressed into the material of the corrugated cylinder.

115 Variations may be resorted to within the scope of the invention, and portions of the improvements may be used without others.

120 Having thus described my invention, I claim:

1. The combination of a peripherally grooved main cylinder over which runs a longitudinally corrugated web, means for pressing one face of the web against the cylinder, and a grooved member to engage the other face of the web, said grooved member meshing with said cylinder and co-operating therewith to form a throat to retard and crinkle the web transversely as it 125 130

- 4
- threads between the cylinder and the grooved member.
2. The combination of a peripherally-grooved main cylinder for carrying a longitudinally corrugated web, and a second peripherally-grooved cylinder meshing with said main cylinder but out of contact therewith, and sufficiently rough to co-operate with said main cylinder to form means for 10 retarding and transversely crinkling the web, the second cylinder revolving at less surface speed than the main cylinder.
3. The combination of a peripherally-grooved main cylinder for carrying a longitudinally corrugated web, and a second peripherally-grooved cylinder meshing with said main cylinder but out of contact therewith, and connected to have a slower surface speed than the main cylinder, and sufficiently rough to co-operate with said main cylinder to form means for retarding and 20 transversely crinkling the web.
4. The combination of a peripherally-grooved main cylinder for carrying a longitudinally corrugated web, and a second peripherally-grooved cylinder meshing with said main cylinder but out of contact therewith, and connected to have a slower surface speed than the main cylinder, and having a roughened surface, and co-operating with said main cylinder to form means for retarding and transversely crinkling the web.
5. An apparatus for transversely crinkling and advancing a web of paper or the like, comprising two corrugated members between which the web advances and by which opposite faces of the web are simultaneously engaged and the web is reduced in speed and transversely crinkled.
6. An apparatus for transversely crinkling and advancing a web of paper or the like, comprising two corrugated members between which the web advances and by which its speed is reduced and it is transversely crinkled, said members being out of contact with each other but sufficiently close together to engage the web on both its faces simultaneously as it threads between them.
7. The method of crinkling a longitudinally corrugated web of paper or the like, consisting in threading it through a constricted undulatory throat to choke the throat and retard the progress of the web, and cause the oncoming web to engage opposite sides of the throat simultaneously and thereby form into crinkles within the throat and to emerge at the delivery end of the throat.
8. An apparatus for crinkling transversely an advancing web of longitudinally corrugated paper or the like, comprising an undulatory throat, said apparatus comprising provision for thrusting the web into and threading it through the throat with both its faces in contact with the throat to choke the same and cause the web to crinkle.
9. An apparatus for crinkling transversely an advancing web of longitudinally corrugated paper or the like, comprising an undulatory throat, said apparatus comprising provision for thrusting the web into and threading it through the throat with both its faces in contact with the throat to choke the same and cause the web to crinkle, and said throat being provided with clearances for the crinkling.
10. An apparatus for crinkling transversely a longitudinally corrugated web of paper or the like, comprising a throat into which the web advances, said throat having means for crinkling certain portions of the web, and leaving other portions uncrinkled.
11. The combination with a revolving corrugated main cylinder around which a moist web of pulp or paper is advanced, of a device to co-operate with said cylinder for the double purpose of crinkling a longitudinally corrugated web transversely and confining it against bulging away from said cylinder, said device co-operating with said cylinder to form a confining undulatory constricted throat through which the web threads and by which the confined web is engaged on its opposite faces and reduced in speed and crinkled.
12. The combination with a revolving corrugated main cylinder around which a moist web of pulp or paper is advanced, of a device to co-operate with said cylinder for the double purpose of crinkling a longitudinally corrugated web transversely and confining it against bulging away from said cylinder, said device co-operating with said cylinder to form a confining undulatory constricted throat through which the web threads and by which the confined web is engaged on its opposite faces and reduced in speed and crinkled, said co-operating device provided with clearances for the crinkling.
13. The process of making paper which is stretchable in all directions, comprising forming longitudinal corrugations in and then advancing a moist web of pulp, semi-pulp or paper into a constricted throat to be threaded through the throat with both its faces in engagement with the throat and to choke the throat and cause the paper to crinkle transversely.
14. The combination of a peripherally-grooved main cylinder for carrying a longitudinally corrugated web, means for pressing the web against the cylinder, and a second cylinder geared to the first cylinder to run at slower surface speed and operating to retard the paper and sufficiently rough to co-operate with the first cylinder to crinkle the paper transversely.
15. The combination of a peripherally-

grooved main cylinder for carrying a longitudinally corrugated web, means for pressing the web against the cylinder, and a second cylinder geared to the first cylinder to run at slower surface speed and operating to retard the paper and sufficiently rough to co-operate with the first cylinder to crinkle the paper transversely, said cylinders being out of contact but placed so close together that the crinkling cylinder 10 engages the web.

16. The combination of a peripherally-grooved main cylinder for carrying a longitudinally corrugated web, means for pressing the web against the cylinder, and a second cylinder geared to the first cylinder to run at slower surface speed and operating to retard the paper and to co-operate with the first cylinder to crinkle the paper 15 transversely, said second cylinder provided with clearances for the crinkling.

17. The combination of a peripherally-grooved main cylinder for carrying a longitudinally corrugated web, means for pressing the web against the cylinder, and a second cylinder geared to the first cylinder to run at slower surface speed and operating to retard the paper and to co-operate with the first cylinder to crinkle the paper 20 transversely, said second cylinder provided with clearances for the crinkling, said clearances in the nature of grooves in the periphery of the crinkling cylinder and extending longitudinally thereof.

18. The combination of a peripherally-grooved main cylinder for carrying a longitudinally corrugated web, means for pressing the web against the cylinder, and a second cylinder geared to the first cylinder to run at slower surface speed and operating to retard the paper and to co-operate with the first cylinder to crinkle the paper transversely, said second cylinder provided with clearances for the crinkling, said clearances 25 in the nature of grooves in the periphery of the crinkling cylinder and extending longitudinally thereof and parallel with the axis of the cylinder.

19. The combination of a peripherally-grooved main cylinder for carrying a longitudinally corrugated web, means for pressing the web against the cylinder, and a second cylinder geared to the first cylinder to run at slower surface speed and operating to retard the paper and to co-operate 30 with the first cylinder to crinkle the paper transversely, said second cylinder provided with clearances for the crinkling, said clearances in the nature of grooves in the periphery of the crinkling cylinder and extending longitudinally thereof, said clearance grooves being nearly or about the same depth as peripheral grooves which run around the crinkling cylinder.

20. The combination of a peripherally-

grooved main cylinder for carrying a longitudinally corrugated web, means for pressing the web against the cylinder, and a second cylinder geared to the first cylinder to run at slower surface speed and operating to retard the paper and to co-operate with the first cylinder to crinkle the paper transversely, said second cylinder provided with clearances for the crinkling, said clearances in the nature of grooves in the periphery of the crinkling cylinder and extending longitudinally thereof, said clearance grooves dividing peripheral ridges formed on the crinkling cylinder into sets of teeth which enter the grooves in the main 75 cylinder to engage and retard the web and effect the crinkling, said teeth having an echelon arrangement.

21. The herein-described means for longitudinally corrugating a web, comprising a 80 corrugated main cylinder of metal or hard material, and a pressure roll having a relatively soft surface to press the web into the corrugations of the main cylinder.

22. The herein-described means for longitudinally corrugating a web, comprising a corrugated main cylinder of metal or hard material, and a pressure roll having a relatively soft surface to press the web into the corrugations of the main cylinder, said soft 85 roll or cylinder having corrugations to mesh with those in the main cylinder.

23. The combination with a peripherally-grooved cylinder around which a longitudinally corrugated web advances, of 100 means co-operating with said cylinder and entering the grooves thereof to form a constricted throat of undulating contour which is choked by the web as it threads therewith, whereby the web is caused to crinkle transversely as it advances through said throat.

24. The combination with a peripherally-grooved cylinder around which a longitudinally corrugated web advances, of means 110 co-operating with said cylinder and entering the grooves thereof to form a constricted throat of undulating contour which is choked by the advancing web, which is caused to crinkle transversely as it advances into said throat, said co-operating means in the form of a corrugated cylinder geared to revolve at slower surface speed than the main cylinder.

25. The combination with a peripherally-grooved cylinder around which a longitudinally corrugated web advances, of means co-operating with said cylinder and entering the grooves thereof to form a constricted 125 throat of undulating contour which is choked by the advancing web, which is caused to crinkle transversely as it advances into said throat, said co-operating means in the form of a corrugated cylinder geared to 130

revolve at slower surface speed than the main cylinder, said co-operative cylinder formed with clearance spaces for the crinkling.

26. The combination of a peripherally-grooved main cylinder for carrying a longitudinally corrugated web, means for pressing the web against the cylinder, and a second cylinder geared to the first cylinder to run at slower surface speed and operating to retard the paper and to co-operate with the first cylinder to crinkle the paper transversely, said second cylinder provided with clearances for the crinkling, said clearances in the nature of grooves in the periphery of the crinkling cylinder and extending longitudinally thereof, said clearance grooves dividing peripheral ridges formed on the crinkling cylinder into sets of teeth which enter the grooves in the main cylinder to engage and retard the web and effect the crinkling, said teeth formed with rear faces which are substantially radial.

27. The combination of a peripherally-

grooved main cylinder for carrying a longitudinally corrugated web, means for pressing the web against the cylinder, and a second cylinder geared to the first cylinder to run at slower surface speed and operating to retard the paper and to co-operate with the first cylinder to crinkle the paper transversely, said second cylinder provided with clearances for the crinkling, said clearances in the nature of grooves in the periphery of the crinkling cylinder and extending longitudinally thereof, said clearance grooves dividing peripheral ridges formed on the crinkling cylinder into sets of teeth which enter the grooves in the main cylinder to engage and retard the web and effect the crinkling, said teeth formed with rear faces which are substantially radial and with advancing faces which are oblique, as set forth.

WILLIAM A. LORENZ.
